UNITED STATES PATENT OFFICE.

GEORGE B. HERINGTON, OF ALHAMBRA, CALIFORNIA.

TICKET-CASE.

1,235,567.

Specification of Letters Patent.

Patented Aug. 7, 1917.

Application filed May 17, 1915. Serial No. 28,596.

To all whom it may concern:

Be it known that I, GEORGE B. HERINGTON, a citizen of the United States, residing at Alhambra, in the county of Los Angeles 5 and State of California, have invented certain new and useful Improvements in Ticket-Cases, of which the following is a specification.

My invention relates to ticket-cases particularly for use in connection with the handling, storing, examining, checking, selling and other manipulation of railway or other transportation tickets of any form, whether card, coupon, book, pad or other styles of 15 tickets.

The object of my invention is to provide a ticket-case for the more convenient and compact storage of tickets ready for sale, and for greater expedition in their sale, 20 thereby saving room and time.

My invention consists essentially in a plurality of ticket-tube-carriers adapted for independent movement in parallel paths, and so mounted and disposed that at one portion 25 of said paths, said carriers will present their ticket-tubes within convenient reach of the selling agent, and in such position that they can readily be removed and replaced. It also consists in the novel ticket-case which I 30 shall now fully describe by reference to the accompanying drawings, in which—

Figure 1 is a front elevation of my ticket-case, its cover being broken in part.

Fig. 2 is a sectional elevation of the same 35 in a plane at right angles to its axis.

Fig. 3 is a detail fragmentary front view showing one of the tube-carriers.

1 is a casing having an opening 2 at its upper inner portion, which opening is provided with a roll-top cover 3. 4 is a shaft 40 mounted in the casing.

Upon this shaft, as an axis, are mounted the rotatable tube-carriers 5. There is a plurality of these carriers, as here shown, 45 and each is independently rotatable. Each carrier comprises a plurality of spaced disks between which the tube-holders, hereinafter described, are mounted. Any suitable power may be applied to turn the carriers on their 50 axis. I have here shown, as the simplest means, the hand rails 6 for manual power.

In order to retain the carriers in any pre-determined position there is mounted on the shaft 4 a ratchet-like disk 7, one for each 55 rotatable carrier. One of these ratchets is shown in Fig. 2. The rotatable carriers

carry the spring controlled pawls 8 adapted to engage with the ratchet 7. This engagement may be adjusted as to pressure, by means of the screws 9. This pawl and 60 ratchet device is of a form which will enable the carriers 5 to move in either direction, but will quickly and accurately bring them to rest when the rotating pressure is removed.

Each carrier 5 is provided, between its 65 component disks, with a circumferential series of tube-holders. These holders may be of various constructions. I have here shown them as sheaths or sleeves 10, which, as shown in Fig. 3, are carried by brackets 11, 70 said sheaths and brackets serving to unite the component disks of each carrier. Each pocket is provided with outstanding ears or brackets 11, which lie against and are secured to the faces of the concentrically arranged disks.

There are any number of these circumferential lines of tube-holders in each carrier, and they may vary in cross section to suit the tubes they are to carry. These holders 80 may be radial, but I prefer to dispose them at an angle to the radial planes as shown in Fig. 2.

In each holder is removably carried a ticket-tube 12. The tubes are slipped into 85 the holders, with their outer ends projecting and preferably beveled, and they are held in the holders, with sufficient pressure by means of the springs 13. The ticket tube holders 10 are adapted to receive the ticket tubes 12, 90 which tubes have an offset side wall 12' near their outer ends, thus increasing the cross sectional area of the outer portion of each tube. This is done in order that the inner portions of the ticket tubes 12 are of less 95 cross sectional area than the outer portions thereof permitting the loose tickets to be maintained in the tubes, yet allowing the free ends of the tickets to separate whereby a single ticket may be readily grasped at a 100 time without disturbing the remaining tickets within a tube. The ticket tube holders 10 have one side wall of less length than the other so as to permit the offset portions 12' of each ticket tube to lie in substantial 105 alignment with the reduced side portions of the holders.

The tubes have various cross sectional dimensions and shapes, as will be seen in Fig. 1, in order to adapt them for the various 110 forms of tickets which are placed in them.

In using the device, the operator turns any

carrier 5 until the tube he wants comes within his sight and reach in the opening 2 of the casing 1.

The ticket-case may be used in any position found most convenient, and being portable, it can be placed where desired. In practice, I prefer to use it as a feature of a ticket-counter, such, for example, as I have shown and described in Patent No. 1,210,802, 10 issued January 2, 1917.

In Fig. 1, the dotted lines at 14 are intended to indicate a counter-top or shelf on each side of my ticket-case.

It will now be seen that a large number 15 of ticket tubes may be spaced in a comparatively small area and still be quickly accessible to a person desiring to extract, insert, or audit or examine their contents, and the tubes themselves may be easily removed 20 and replaced, for filling them or for repairs.

I claim:—

1. A ticket case comprising a suitable casing having an open portion, a plurality of carriers disposed parallel with each other 25 mounted in said casing for rotation past the opening therein, a plurality of separated individual holders attached to the side portions of said parallel carriers and suspended therebetween, ticket tubes removably seated 30 in said holders and having open outer ends accessible from the opening within the casing, and means for retaining said ticket tubes within the holders, substantially as described.

2. A device of the character described 35 comprising a rotatable carrier, ticket tube

holders supported thereby, and each having one side wall of a length greater than the other, removable open-ended ticket tubes adapted to receive a supply of tickets within 40 said holders, each tube having an offset side wall near its open end portion, whereby the ticket receiving space of each tube is abruptly enlarged near its outer end.

3. A device of the character described 45 comprising a rotatable carrier, ticket tube holders supported thereby, and each having one side wall of a length greater than the other, removable open-ended ticket tubes adapted to receive a supply of tickets within 50 said holder, each tube having an offset side wall near its open end portion, whereby the ticket receiving space of each tube is abruptly enlarged near its outer end, the offset walls of the ticket tube holders being disposed in substantial alinement with the upper edges of the short side walls of the holders, substantially as described.

4. A device of the character described 55 comprising a holder, a ticket tube supported thereby, the said tube having an offset side wall near its outer open end, whereby the ticket-receiving cavity is abruptly enlarged near its outer end to permit the ends of the tickets within the tube to separate.

In testimony whereof I have signed my name to this specification in the presence of two subscribing witnesses.

GEORGE B. HERINGTON.
